UNITED STATES PATENT OFFICE.

CLEMENS W. ACKERMANN, OF CHICAGO, ILLINOIS, ASSIGNEE TO FROG SWITCH AND MANUFACTURING COMPANY, OF CARLISLE, PENNSYLVANIA, A CORPORATION OF PENNSYLVANIA.

ROCK CRUSHER.

1,424,792.

Specification of Letters Patent. Patented Aug. 8, 1922.

Application filed December 29, 1919, Serial No. 347,923. Renewed June 12, 1922. Serial No. 567,742.

To all whom it may concern:

Be it known that I, CLEMENS W. ACKERMANN, a citizen of the United States, residing at 1937 Kimball Avenue, Chicago, in the county of Cook and State of Illinois, have invented a certain new and useful Improvement in Rock Crushers, of which the following is a full, clear, concise, and exact description, reference being had to the accompanying drawings, forming a part of this specification.

My invention relates to rock crushers, and more specifically to crushers of the gyratory type, employing a crushing head which 15 gyrates in a conical crushing chamber.

From the nature of the work the surfaces of the crusher head are subject to a severe erosion, which necessitates their frequent renewal, and it is the primary object of the 20 present invention to reduce the expense and difficulty involved in renewing these crushing surfaces. The general practice at present is to construct the crusher head with a removable mantle of manganese steel or the 25 like, which, after considerable wear is removed as an entirety and substituted by a new mantle.

This practice of renewing the mantle as an entirety is subject to the disadvantage, 30 however, that the erosion of the mantle is usually not uniformly distributed over the entire surface, but is more severe and more rapid at the lower end of the cone. The mantle must, therefore, be renewed after 35 a relatively short period of operation because of the intense erosion of these lower surfaces, while the upper surfaces are in comparatively good condition and capable of giving considerable more service. The 40 reason for this non-uniformity of wear of the mantle is due to several reasons, particularly to the action of the small pieces of rock packing into a relatively solid mass in the constricted portion of the crusher 45 throat adjacent the lower end of the mantle so that there is a more continuous breaking action intensified about this end of the mantle.

It is a secondary object of the present invention to provide an improved construction of sectional mantle which permits of 50 renewal of the lower portion of the mantle independently of the upper portion with-

out impairing the rigidity and durability of the crusher head or mantle.

Another object of the invention is to provide an improved method of rigidly locking the plurality of mantle sections together and of rigidly mounting the assembled mantle upon the head center.

Another object is to provide an improved construction and relation of locking key for locking the two mantle sections together. These improved locking keys are independent of either mantle section, so that in the 65 event of breakage of one or more of the keys there is no damage done to the mantle sections.

The manner of practicing my invention will be more apparent from the following 70 detailed description, taken in connection with the accompanying drawings, in which I have illustrated one preferred embodiment of my invention.

In the drawings:

Figure 1 is a vertical sectional view of 75 a gyratory crusher employing a sectional mantle constructed in accordance with my invention;

Figure 2 is a fragmentary elevational 80 view illustrating a modified construction of sectional mantle;

Figure 3 is a plan view of the crusher head;

Figure 4 is an enlarged vertical sectional 85 view of the crusher head;

Figure 5 is a vertical sectional view of the upper mantle section;

Figure 6 is a similar view of the lower 90 mantle section;

Figures 7, 8 and 9 are different enlarged 95 views of the preferred form of locking key, and

Figure 10 is a fragmentary sectional view illustrating a modified relation of the locking keys and mantle sections.

The crusher 1, which I shall describe briefly, includes the conical crushing chamber 2, the feeding hopper 3 and the discharge spout 4, which discharges the crushed rock 100 from the bottom of the chamber 2. The upper end of a main oscillatory shaft 5 is loosely guided in a play bearing in the hub of a spider 6. The lower end of the oscillatory shaft 5 is mounted in an eccentric 8, 105 which receives its driving energy from the

pulley 9 through the bevel gears 10 and 11. On the shaft 5 is mounted the conical crushing head 12, the inclined taper of which in cooperation with the oppositely inclined 5 walls of the chamber 2 forms a tapering throat in which the actual rock breaking is accomplished.

It will be apparent that the gravitation of the smaller pieces of rock down into the 10 restricted portion 14 of this throat will produce a relatively dense concentration of rock about the lower end of the crusher head, and as a result, these crushing surfaces will be more intensely eroded. This action 15 is accentuated by the greater range of movement in the lower end of the crusher head, and also because of the fact that the smaller pieces of rock are broken more by direct compression than by the action of spanning 20 a portion of the chamber and being broken by bending, as in the upper portion of the crusher chamber. The manganese steel mantle which constitutes the crushing surface of the head 12 is divided into upper 25 and lower sections 15 and 16. Referring to Figure 4, these sections are mounted on a tapering head center or core 18, which is preferably composed of cast iron or steel. The mounting of the head center 18 on the 30 shaft 5 may be accomplished in any preferred manner. In the embodiment shown, the head center is bored out on a taper to fit over the taper portion 19 of the shaft 5, on which the head center is held by a nut 21 35 or by any other suitable means. The head center 18 is preferably keyed to the shaft 5 to prevent rotation of the head center. It will be noted that the intermediate portion of each mantle section is spaced away from 40 the tapered center 18, the actual bearing contact of the mantle sections on the head center being confined to the inwardly projecting flanges 22 and 23 on the upper mantle section 15, and the flanges 24 and 25 45 on the lower mantle section 16.

This eliminates an extensive machining operation, as by this arrangement only the flanges and their points of contact on the head center require machining. It will be 50 noted from Figures 5 and 6 that the interior of each of the mantle sections 15 and 16 is formed with a plurality of longitudinal grooves 26-27 and also a plurality of annular grooves 28-29. The series of longitudinal grooves 26 and 27 are extended through 55 the flanges 22, 23 and 24 and the mantle sections are assembled upon the head center 18 with these grooves in alignment so that when the molten zinc filler is poured between the 60 mantle sections and head center, it will permeate down and entirely fill the intervening spaces between the mantle sections and core. This filler, which is preferably of zinc or babbitt constitutes a backing for the portions 65 of the mantle sections which are spaced

away from the head center and thus forms a solid unit of the mantle sections and center. It will be apparent that this filler, which is designated 30, also assists in locking the two mantle sections together by joining the sections through the aligned grooves 26 and 27. 70

Referring now to the locking connections between the mantle sections, it will be noted that the adjoining edges of both sections are provided with corresponding openings 75 31-32, which are adapted for the reception of locking keys 33. There are preferably three of these sets of openings, spaced equidistantly about the mantle sections. 80

The keys are constructed of manganese steel or the like and are preferably shaped with a figure 8 formation. The middle portion of the 8 configuration is relatively wide to afford ample strength against the lateral shearing and breaking stresses, which 85 result from the tendency of the mantle sections to rotate relatively to each other. The sides of the keys are tapered or beveled, as indicated at 34, these tapered surfaces co-operating with corresponding tapered surfaces 35, formed in the openings 31 and 32. The two tapers 34 and 35 are formed to converge outwardly for the purpose of locking 90 the keys in the openings; this locking function being assisted by the camming action of 95 the tapered surfaces under the relative rotative tendency between the two mantle sections, which tends to force the keys inwardly against the head center 18. As a result of the locking relation of the keys there is no 100 possibility of any of the keys working out of the mantle openings. The keys are made slightly smaller than the mantle openings and the intervening spaces are adapted to be filled by the spelter filling 30, as indicated at 105 36. This construction avoids the necessity of accurately machining the keys or the locking openings, and furthermore, insures a more rigid mounting of the keys in the openings than would even be possible by machining the same. 110

In assembling the mantle for mounting on the head center, the three keys 33 are first inserted into the openings 31 and 32 from the inside of the mantle sections, whereupon 115 the mantle is slipped down over the head center 18 and the flanges 22, 23, 24 and 25 are brought down firmly on the machined surfaces of the head center. The spelter filling is then poured between the head center and the mantle sections to join the different parts into a rigid unit. The mantle is held on the head center by any preferred means, such as by flowing a filling of zinc between the top of the mantle and the nut 21 120 and utilizing this nut for locking the mantle on the head center, or by any other means. 125

When the erosion of the lower mantle section necessitates its renewal, the mantle as an entirety is first released from the head 130

center by releasing the nut 21 or whatever locking means is employed for holding the mantle in position. The filler does not cohere molecularly to the head center, nor to 5 the mantle sections, and consequently these can be released without any difficulty. After removal of the mantle the filler is released from the mantle sections and the keys are disengaged to release the mantle sections 10 from each other. A new lower mantle section is then substituted and the keys are reinserted. The assembled mantle is then slipped back over the head center and the spelter filling flowed between the two as 15 hereinbefore described.

In Figure 10, I have illustrated a modified relation of the locking keys and mantle sections. In this embodiment the locking openings 31' and 32' are not extended entirely 20 through the walls of the mantle sections, but only part way, so as to form internal recesses in the sections. The keys 33' are inserted in the recesses from the inside of the mantle sections and are locked therein by the 25 zinc filler 30'. By this construction the mantle presents a smooth outer crushing surface and furthermore there is no possibility of damaging the keys or loosening their mounting in the key openings 31' and 32' by engagement with the rocks on the crusher 30 throat.

In Figure 2 I have illustrated a modified construction of mantle designed to rigidly lock the mantle sections together independently of the locking keys. To this end the adjoining edges of the two sections are formed with cooperating serrations or saw-teeth 40, which are held in engagement by the locking keys 33. These serrations or saw 40 teeth are provided for the purpose of relieving the locking keys of the strain of locking the sections together against the rotative force created by the crushing operation, which tends to turn the mantle sections relative to each other.

It should be noted that by making the locking keys entirely independent of the mantle sections, the loss involved in the breakage of one or more of these keys is 50 negligible as compared to the loss involved where the keys are formed integral with one or both of the mantle sections and the breakage of any one of the keys ruins its corresponding mantle section. It is to be understood, however, that the present form of 55 key may be extensively modified and that the invention is not to be limited to any particular formation or construction of these keys.

60 I claim:

1. In a mantle for a crusher head, the combination of a head center, a mantle comprising an upper and a lower mantle section mounted on said head center, the adjoining 65 edges of said mantle sections being provided

with registering locking recesses terminating at points intermediate the ends of said mantle sections; a separate locking key independent of both mantle sections for locking said sections together, said locking key having enlarged end portions engaging in the co-operating recesses. 70

2. In a mantle for a crusher head, the combination of a plurality of independent mantle sections, the adjoining edges of said 75 mantle sections being provided with coincident locking recesses, a separate locking key independent of said mantle sections for locking said sections together, said locking recesses being formed with beveled side walls 80 adapted to cooperate with beveled lateral surfaces on said locking key for positively locking said key against outward displacement.

3. In a mantle for a gyratory crusher 85 head, the combination of an upper and a lower mantle section, a plurality of keys for locking said sections together, said keys extending between the adjoining edges of said upper and lower mantle sections and engaging 90 in correspondingly formed key openings in said mantle sections, and a filler between said keys and the walls of said openings.

4. In a mantle for a gyratory crusher head, the combination of an upper and a 95 lower mantle section, and a plurality of keys independent of said sections for locking said sections together, said keys being of substantial figure 8 formation, said 100 mantle sections being provided with correspondingly formed openings adapted to coincide for the reception of said locking keys, the ends of said openings terminating intermediate the ends of said mantle sections and being enlarged to receive the ends of said 105 keys.

5. In a gyratory crusher, a head center, a mantle comprising an upper and a lower mantle section mounted on said head center, said mantle sections having inwardly projecting flanges adjacent their ends for engagement on said head center, a plurality of keys independent of said mantle sections for locking said sections together, said mantle sections having coincident openings in their 110 adjoining edges for the reception of said keys, and a metallic filler between said head center and said mantle sections and between said keys and the sides of said openings. 115

6. In a mantle for a gyratory crusher 120 head, the combination of a head center, a mantle comprising an upper and a lower mantle section mounted on said head center, the adjoining edges of said mantle sections being formed with a continuous series of 125 saw-tooth serrations in meshed relation for preventing relative rotation between said mantle sections, the adjoining edges of said mantle sections also being provided with continuous locking recesses, the ends of 130

which terminate in the body of said mantle sections at points intermediate the ends of said mantle sections, and a plurality of separate locking keys independent of both 5 mantle sections for locking said sections together, each of said locking keys having a reduced intermediate portion and enlarged

end portions having interlocking engagement in correspondingly formed ends in said locking recesses.

In witness whereof, I hereunto subscribe my name this 26th day of December, 1919.

CLEMENS W. ACKERMANN.
